UNITED STATES PATENT OFFICE.

MATHIAS G. MUELLER, OF COLOME, SOUTH DAKOTA.

FOWL-BOOT.

1,207,196.

Specification of Letters Patent.

Patented Dec. 5, 1916.

Application filed April 12, 1916. Serial No. 90,725.

To all whom it may concern:

Be it known that I, MATHIAS G. MUELLER, a citizen of the United States, residing at Colome, in the county of Tripp and State 5 of South Dakota, have invented certain new and useful Improvements in Fowl-Boots, of which the following is a specification.

This invention relates to a fowl boot and the primary object is to provide a boot that 10 may be attached to the leg of the fowl for preventing the fowl from assuming a sitting position and at the same time allowing free movement of the legs for scratching, walking or roosting.

15 The invention also aims to provide a boot that may be constructed of thin metal and attached to the leg of a fowl for limiting or restricting the bending movement of the leg of the fowl thus breaking the fowl of an 20 inclination to sit on the eggs which it lays.

An object of the invention is to construct the device in a manner that will obviate the possibility of fowls jumping over barn-yard or poultry-yard fences, the device preventing 25 the fowls from crouching to assume a springing position.

As a further object of the invention the device contemplates the provision of means for lengthening the shank portion of the 30 boot whereby the boot may be used for different sizes of fowls.

A further object of this invention is the provision of a fowl boot which consists of comparatively few parts and is simple in 35 construction, but durable and well adapted to withstand the rough usage to which devices of this character are ordinarily subjected.

For a full description of the invention 40 and the advantages and merits thereof, reference is to be had to the following description and the accompanying drawings, wherein is illustrated the preferred form of my invention, in which;

45 Figure 1 is a side elevation showing the device applied to the leg of a fowl. Fig. 2 is a horizontal section on the line 2—2 of Fig. 1. Fig. 3 is a transverse section on the line 3—3 of Fig. 1.

50 The device consists of the thigh boot 1 and the shank boot 2, both being constructed of thin light metal such as aluminum. The thigh boot 1 fastens around the thigh of the leg of the fowl by a strap 3 which is 55 fastened to a button 4 carried by one side of the thigh boot 1. At each side of the thigh

boot and depending from the lower end thereof is a pair of ears 5 which are provided with central apertures 6 for receiving a hinge pin 7. It will be observed that the 60 rear of the boot 1 is open and, in applying the device to the leg of the fowl, the boot, being of comparatively thin material, may be sprung open to insert the leg of the fowl.

The shank boot 2 is designed to partially 65 surround the shank of the leg of the fowl and the upper end is provided with ears 8 which are provided with central apertures for receiving one end of one of the hinge pins 7. For limiting the backward swinging 70 movement of the shank boot 2, I provide the upper edges of the shank boot with flanges 9 which are bent over the ears 5 of the thigh boot 1 as indicated by Fig. 3 of the drawing. A strap 10 has one end secured to one side 75 of the thigh boot 2 and the free end of the strap is provided with apertures for engaging the fastening button 11 whereby the shank boot may be fastened snugly to the shank of the fowl.

80 The lower end of the shank boot 2 has adjustably mounted thereon the extension sleeve 12 and the shank boot 2 has struck-out portions adjacent each edge thereto to provide fastening shanks 13 which extend 85 through a longitudinal slot 14 in the sleeve 12. The sleeve 12 is thereby free to be moved up or down for extending the length of the shank boot 2 in the event of it being necessary to attach it to a fowl having 90 longer or shorter legs. For fixing the sleeve in adjusted position, I provide the inner face of the boot adjacent the lower end thereof with a struck-out portion 15 which is adapted to register with one of a plurality 95 of struck-out portions 16 formed in the front of the sleeve 12. The struck-out portion 15 may be moved into one of the struck-out portions 16 thereby fixing the sleeve 12 in the desired adjusted position.

100 Mounted on one side of the sleeve 12 is a number plate 17 which has its vertical edges extended into slits 18 formed in the sleeve 12. The number plate bears a numeral which may be used to identify the 105 fowl and to determine the length of time that the boot has been worn by the fowl. The thigh boot 1 and the shank boot 2 are provided with cut-out portions 19 and 20 adjacent their meeting ends as indicated by 110 Fig. 1 of the drawing. These cut-out portions allow the joint of the fowl to be freely

5 moved and the points or edges 21 and 22 which are formed at the termination of the cut-out portions 19 and 20, are adapted to contact when the leg of the fowl has been bent to the pre-determined point of movement, thus preventing the fowl from assuming a position that will allow it to "set."

10 When a fowl is inclined to brood or "set," the device will be fixed upon the leg of the fowl or, if it is thought desirable, one may be fixed to each leg of the fowl. It is pointed out that the device will be especially useful in preventing the fowls from jumping over fences, the boot preventing the legs 15 of the fowl from being bent to assume springing position.

20 From the foregoing it will be observed that a very simple and durable fowl boot has been provided, the details of which embody the preferred form. I desire it to be understood however, that slight changes or 25 modifications in the minor details of construction may be made without departing from the spirit of the invention or the scope of the claims hereunto appended.

I claim:

1. In a device of this character comprising a shank boot, means for securing the shank boot to the leg of the fowl, and 30 a thigh boot hingedly mounted on the upper end of said shank boot, said shank boot and said thigh boot each provided with a cut-out portion adjacent the meeting ends thereof whereby the said shank boot and 35 said thigh boot will contact at a pre-determined point of movement.

40 2. In a device of the character described comprising a shank boot, means for securing the shank boot to the leg of the fowl, a thigh boot hingedly mounted on the upper end of said shank boot, said shank boot and said thigh boot each provided with a cut-out portion adjacent the meeting ends thereof whereby said shank boot and said thigh 45 boot will contact at a pre-determined point of movement, and means for extending the length of said shank boot.

50 3. In a device of the character described comprising a shank boot, means for securing the shank boot to the leg of the fowl, a thigh boot hingedly mounted on the upper end of

said shank boot, said shank boot and said thigh boot each provided with a cut-out portion adjacent the meeting ends thereof whereby the said shank boot and said thigh 55 boot will contact at a pre-determined point of movement, and an extension sleeve mounted on the lower end of said shank boot and provided with a plurality of struck-out portions, the lower end of said 60 shank boot also provided with struck-out portions adapted to register with one of the struck-out portions on said sleeve.

4. In a device of the character described comprising a shank boot, means for securing 65 the shank boot to the leg of the fowl, a thigh boot hingedly mounted on the upper end of said shank boot, said shank boot and said thigh boot each provided with a cut-out portion adjacent the meeting ends thereof 70 whereby said shank boot and said thigh boot will contact at a pre-determined point of movement, an extension sleeve mounted on the lower end of said shank boot and provided with a plurality of struck-out portions, the lower end of said shank boot also 75 provided with struck-out portions adapted to register with one of the struck-out portions on said sleeve, and fastening straps carried by the shank boot and the thigh 80 boot whereby the boot may be fastened to the leg of the fowl.

5. In a device of the character described comprising a shank boot, a fastening element for securing the shank boot in position, 85 a thigh boot hingedly mounted on the upper end of the shank boot, the said shank boot and the said thigh boot being provided with a cut-out portion adjacent their meeting ends whereby the said boots will contact 90 when pivotally moved at a pre-determined point for restricting the relative movement of the said boots, flanges carried by the shank boot and adapted to embrace the corresponding portion of the thigh boot. 95

In testimony whereof I affix my signature in presence of two witnesses.

MATHIAS G. MUELLER.
